MANUFACTURE OF GASOLINE

Harold V. Atwell and Frank H. Bruner, Beacon, N. Y., assignors, by mesne assignments, to The Texas Company, New York, N. Y., a corporation of Delaware

Application January 27, 1939, Serial No. 253,052

14 Claims. (Cl. 196—10)

This invention relates to the manufacture of high antiknock gasoline hydrocarbons by the alkylation or condensation of low boiling isoparaffins, such as isobutane or isopentane, with olefins, particularly normally gaseous olefins or polymers thereof. The invention has to do particularly with improvements in the alkylation of normally gaseous hydrocarbons containing propylene, whereby the efficiency and facility of the operation are increased.

In the alkylation of isobutane or isopentane with cracking still gases, preferably those predominating in C₃ and C₄ hydrocarbons, it is often advantageous to separate the C₃ hydrocarbons from the C₄ hydrocarbons and then concentrate the propylene which may be used along with the C₄ hydrocarbons in the alkylation operation. The separation of the C₄ hydrocarbons from the C₃ hydrocarbons may be accomplished by straight fractionation or absorptive rectification with an oil absorbent but the separation of the propylene from the propane is more difficult. It is advantageous to separate from the charge to an alkylation system the propane which is often present in relatively large amounts in the C₃ fraction, since it would build up in the system and cause undue dilution of the reactive constituents. We have found that the propylene may be advantageously absorbed in concentrated sulfuric acid without substantial polymerization, providing there are no large amount of butenes present. The resulting mixture of acid and absorbed propylene is suitable for use in the alkylation operation.

It is desirable to carry out the alkylation of isobutane with normally gaseous olefins in the liquid phase and this can be done at ordinary temperatures with relatively low superatmospheric pressure, in the case of C₄ hydrocarbons. When large amounts of C₃ hydrocarbons are used, however, greater difficulty is encountered in maintaining the liquid phase due to the volatility of the mixture, particularly when large amounts of propane are present. It has been found that an advantageous method of operation is to absorb the propylene in concentrated sulfuric acid and then introduce the mixture into the system under approximately the liquid phase conditions which are used when alkylating substantially only C₄ hydrocarbons.

The invention will be more fully understood from the following description read in connection with the accompanying drawing which shows a diagrammatical sketch of one form of apparatus for carrying out the process of the invention.

In the following description, the invention is described in connection with the treatment of gases from an adjacent cracking still but it is to be understood that suitable unsaturated gaseous hydrocarbons from any source may be treated. In the modification shown in the drawing, a cracked unstabilized naphtha from an adjacent cracking still is introduced through the line 1 to a cracking plant accumulator or depropanizer 2. This accumulator may be connected directly with the cracking still whereby substantially all the gases and liquids from the still are collected; or the accumulator may be for the purpose of receiving distillate from a receiver 15 in which all or a portion of the fixed gases, such as hydrogen, methane and C₂ hydrocarbons have been released. It is intended that the product collected in the accumulator 2 contain substantially all of the C₃ and C₄ hydrocarbons. 20 The pressure maintained on the accumulator 2 may depend on the volatility of the stabilized naphtha desired. If a stabilized naphtha of approximately 10 pounds Reid vapor pressure is intended to be produced, then the accumulator 25 may be under a pressure of approximately 50 pounds. If a stabilized naphtha of about 14 pounds Reid vapor pressure is intended to be produced, then the accumulator drum may advantageously be maintained under a higher pressure, for example about 150 pounds. When the accumulator is maintained under lower pressure, the gaseous hydrocarbons released therefrom through vapor line 5 will contain substantial amounts of C₄ hydrocarbons in addition to the 30 C₃ hydrocarbons, whereas if the higher pressure is maintained on the accumulator drum, the gases withdrawn through the line 6 may be substantially free from C₄ hydrocarbons. 35 In case the gases removed from the accumulator 2 contain substantial amounts of C₄ hydrocarbons, it is advantageous to separate the C₄ hydrocarbons from the C₃ hydrocarbons since it has been found that substantial amounts of C₄ hydrocarbons cause undue polymerization or hydropolymerization when the gases are contacted with concentrated sulfuric acid for the purpose of absorbing propylene. If the gases contain amounts of C₄ hydrocarbons, particularly butenes, in excess of about 5%, then the gases are 40 passed through lines 5 and 6 to an absorber 8 wherein they are scrubbed with an absorbent oil such as mineral seal, introduced into the upper portion of the absorber through the line 16. In the absorber it is intended to scrub out from the 45 gases substantially all the C₄ hydrocarbons from 50 55 60 65 70 75 80 85 90 95 100

the C₃ hydrocarbons which are released from the upper portion of the absorber through the line 9 and thereafter passed through the line 10 to an acid absorber 12, referred to hereinafter. The enriched oil is withdrawn from the lower portion of the absorber through the line 14 and introduced into the stripper 15 wherein the absorbed hydrocarbons are distilled from the absorbent which is withdrawn in a lean condition from the lower portion of the stripper 15 and reintroduced into the absorber through the line 16. The distilled C₄ hydrocarbons are withdrawn from the upper portion of the stripper through the line 18, and conducted to the condenser 20, referred to hereinafter.

In case the gases removed from the accumulator 2 through the line 5 contain relatively small amounts of C₄ hydrocarbons, particularly butenes, for example about 5% or less, these gases may be conducted directly to the absorber 12 through the lines 21 and 10. When the gases contain such small amounts of butenes, it has been found that propylene may be absorbed from the gases by concentrated sulfuric acid without substantial polymerization or hydropolymerization of the olefins.

In the absorber 12 the gases are scrubbed with sulfuric acid introduced into the upper portion thereof through the line 22. This acid should be of at least 90% concentration, and preferably about 94% or stronger. A temperature suitable for the absorption of propylene, preferably under 30° C., is maintained in the absorber. The propylene is substantially entirely absorbed by the acid and the unabsorbed gases, principally propane, are released from the top of the absorber through the line 23. The mixture of acid and absorbed propylene is withdrawn from the lower portion of the absorber, and passed through the line 25, containing a pump 26, to a reactor 28.

A cracked naphtha containing C₄ hydrocarbons is withdrawn from the accumulator 2 and passed through the line 30 to the stabilizer 32. In the stabilizer the naphtha is stabilized to substantially commercial gasoline specifications, although all or any portion of the C₄ hydrocarbons may be removed and in case the stabilized naphtha is deficient in volatility, normal butane may be added thereto to bring up the volatility. The stabilized naphtha is withdrawn from the lower portion of the stabilizer through the line 33. The normally gaseous hydrocarbons separated from the naphtha in the stabilizer are withdrawn from the upper portion thereof through the line 35 and may be passed to the absorber 8. The treatment of these gases in the absorber 8 is desirable in case the gases contain any substantial amount of C₃ hydrocarbons whereby a separation of the C₃ hydrocarbons from the C₄ is accomplished in the absorber. If the gaseous hydrocarbons removed from the top of the stabilizer contain substantially only C₄ hydrocarbons, then they may be conducted through the line 36 directly to the condenser 20, referred to heretofore. In the condenser the C₄ hydrocarbons are cooled and condensed and the condensate passed through the run-down line 37 to a receiver 38. The products collecting in the receiver 38, including normal butane, isobutane and isobutenes, are conducted through the line 48 in which is located a pump 41, to the reactor 28.

In the reactor 28 it is intended that alkylation

or condensation of isobutane with the olefins, including butenes and propylene, take place in the presence of sulfuric acid as a catalyst. The conditions suitable for such reaction are temperatures of about 60° to 100° F. and preferably about 65° to 70° F. The products should be intimately contacted, for example by suitable stirring mechanism, such as the stirrer 43. Sufficient pressure is held in the reactor to maintain the hydrocarbons substantially in the liquid phase. The sulfuric acid should be of about 90 to 100% strength, and preferably about 94 to 98% concentration. The amount of acid should be sufficient to provide an acid dosage of about equal to that of the olefins by weight. The acid from the absorber 12 may be of sufficient strength and volume to satisfy the requirements in the reactor 28, although it is contemplated that fresh or recycle acid in suitable amount and in sufficient strength may be used to provide the volume and concentration requirements of the acid in the reactor. A relatively high ratio of isobutane to olefins, for example between about 3:1 and 5:1, is desirable and, if it is necessary to add additional isobutane other than that contained in the C₄ hydrocarbons from the receiver 38, this additional isobutane may be introduced through the line 45 by the pump 46.

The reaction products are transferred from the reactor 28 through the line 48 to a settler 50 wherein the acid is allowed to settle out in the lower portion thereof, and may be withdrawn therefrom through the line 51 and discharged from the system or recycled, with or without revivification, to the reactor 28. The hydrocarbons collecting in the upper portion of the settler are withdrawn and passed through the line 52 to a neutralizer 55, wherein the hydrocarbons are contacted with a neutralizing agent, such as aqueous caustic alkali or soda, introduced into the upper portion of the neutralizer through the line 56 by the pump 58. In the neutralizer 55 the hydrocarbons are intimately contacted with a neutralizer and any acidity removed. The spent alkali is withdrawn from the lower portion of the neutralizer through the line 60 and may be recycled, if desired. The neutralized hydrocarbons are withdrawn from the upper portion of the neutralizer through the line 61 to a stabilizer 62. If necessary, a settler may be provided between the neutralizer 55 and the stabilizer 62 to separate the spent alkali.

In the stabilizer 62 the hydrocarbons are stabilized to produce a liquid product containing sufficient butane to satisfy the volatility requirements of the gasoline product when the latter is separated therefrom. The excess butane, together with other C₄ hydrocarbons is removed overhead from the stabilizer and conducted through the line 64 to fractionator 65. In the fractionator 65 a separation is made between the isobutane and the normal butane. The normal butane is condensed and collected as a liquid in the lower portion of the fractionator and may be withdrawn from the bottom thereof through the line 66 and discharged from the system or passed through the line 67 by the pump 68 for blending with the stabilized naphtha withdrawn from the stabilizer 32. The isobutane is withdrawn from the top of the fractionator 65 through the line 70 and compressed by the compressor 71. The compressed hydrocarbons are cooled in the cooler 72 sufficiently to effect condensation thereof and the liquids are passed

through the line 73 to the reactor 28 to undergo further reaction.

The liquids withdrawn from the bottom of the stabilizer 62 are passed through the line 75 by the pump 76 to fractionator 78 wherein the product is fractionally distilled to separate a product boiling within the gasoline boiling point range. The hydrocarbons of higher boiling point than gasoline are withdrawn as bottoms from the lower portion of the fractionator 78 through the line 80. The gasoline vapors are conducted overhead from the fractionator 78 through the line 81 and condenser 82 to a receiver 84. The product collecting in the receiver 84 consists essentially of saturated hydrocarbons of high anti-knock value, and suitable for the manufacture of gasoline motor fuel.

As an example of the operation of the invention, cracked naphtha from a cracking still is collected in an accumulator maintained under a pressure of about 50 pounds per square inch. Gases and vapors are released from the accumulator and passed to an absorber wherein they are scrubbed with an absorbent oil to remove substantially all the C₄ hydrocarbons, which are later distilled from the rich absorbent. The unabsorbed hydrocarbons from the absorber are passed to an acid absorber wherein they are contacted with sulfuric acid of about 94% concentration, whereby the propylene is absorbed. The mixture of acid and absorbed propylene is then charged to an alkylation reactor. A naphtha is withdrawn from the cracking plant accumulator and charged to a stabilizer from which a stabilized naphtha of about gasoline volatility is produced. Vapors from the stabilizer consisting essentially of C₄ hydrocarbons are condensed to form a liquid C₄ hydrocarbon fraction which is also charged to the alkylation reactor. Sufficient isobutane is charged to the reactor to maintain an overall ratio of isobutane to olefins in the feed of about 3:1. The hydrocarbons in the reactor are intimately contacted in the liquid phase with the acid at a temperature of about 65° F. for sufficient time to effect substantial alkylation of the isobutane with the butenes and propylene. The acid is removed from the reaction products and the hydrocarbons neutralized. The product is then stabilized to produce a liquid fraction of substantially gasoline boiling point range and volatility. The overhead from the stabilizer is fractionated to separate out the normal butane from the isobutane and the isobutane recycled to the alkylation operation. A gasoline product corresponding to a yield of about 150% based on the olefins, and having an octane value of about 85 is obtained.

Obviously many modifications and variations of the invention, as hereinbefore set forth, may be made without departing from the spirit and scope thereof, and therefore only such limitations should be imposed as are indicated in the appended claims.

We claim:

1. A process for the manufacture of high anti-knock gasoline hydrocarbons, which comprises absorbing propylene in concentrated sulfuric acid of alkylation strength, and then treating the mixture with isobutane and a butene in the liquid phase under alkylation conditions effective for the alkylation of said butene by the isobutane, whereby the absorbed propylene is also alkylated by the isobutane under these conditions to produce saturated hydrocarbons of high anti-knock value within the gasoline boiling range.

2. A process for the manufacture of high anti-knock gasoline hydrocarbons, which comprises forming a mixture of propylene and concentrated sulfuric acid of alkylation strength, then treating the mixture with isobutane and butenes in the liquid phase under alkylation conditions effective for the alkylation of said butenes by the isobutane, whereby the absorbed propylene is also alkylated by the isobutane under these conditions to produce saturated hydrocarbons of high anti-knock value boiling within the gasoline boiling range.

3. A process for the manufacture of high anti-knock gasoline hydrocarbons, which comprises absorbing propylene in sulfuric acid without substantial polymerization thereof by contacting gaseous propylene with concentrated sulfuric acid, then alkylating isobutane and butenes, in the liquid phase, with the sulfuric acid and propylene mixture, while maintaining the concentration of the acid in the alkylation zone at about 90 to 98%.

4. A process for the manufacture of high anti-knock gasoline hydrocarbons, which comprises treating under alkylation conditions C₄ hydrocarbons including butenes and isobutane in the liquid phase at about atmospheric temperatures with a solution of propylene absorbed in concentrated sulfuric acid of alkylation strength and separating from the reaction mixture saturated, high antiknock hydrocarbons within the gasoline boiling range.

5. A process for the manufacture of high anti-knock gasoline hydrocarbons, which comprises treating with concentrated sulfuric acid a normally gaseous hydrocarbon mixture containing as the olefin content thereof mainly propylene and not more than a small amount of butenes, whereby the propylene is absorbed in the acid without substantial polymerization, and then intimately contacting the said acid mixture under alkylation conditions effective for the alkylation of C₄ hydrocarbons with an excess of isobutane and in the presence of a C₄ olefin, whereby the absorbed propylene and the C₄ olefin are alkylated by the isobutane to form high anti-knock saturated hydrocarbons within the gasoline boiling range.

6. A process according to claim 5 in which the amount of butenes in the hydrocarbon mixture is not in excess of about 5%.

7. A process for the manufacture of high anti-knock gasoline hydrocarbons, which comprises treating a gas containing mainly propylene and butenes in sufficiently small amounts that substantially no polymerization occurs with concentrated sulfuric acid to absorb the propylene, then contacting the acid mixture under alkylation conditions with butenes and excess isobutane whereby the isobutane is alkylated by the absorbed propylene and butenes to form high anti-knock gasoline hydrocarbons.

8. A process for the manufacture of high anti-knock gasoline hydrocarbons, which comprises separating unsaturated normally gaseous hydrocarbons into a light fraction containing mainly hydrocarbons of less than 4 carbon atoms and a heavy fraction containing mainly hydrocarbons of 4 carbon atoms including butenes, separating propylene from the light fraction by absorption in concentrated sulfuric acid, then contacting under alkylation conditions said absorbed propylene and said heavy fraction in the presence of excess isobutane and concentrated sulfuric acid of alkylation strength whereby the isobutane is

alkylated with the absorbed propylene and butenes, and separating from the reaction products gasoline hydrocarbons of high antiknock value.

9. A process for the manufacture of high antiknock gasoline hydrocarbons, which comprises fractionating unsaturated normally gaseous hydrocarbons into a light fraction predominating in C₃ hydrocarbons and a heavy fraction predominating in C₄ hydrocarbons, scrubbing the light fraction with sulfuric acid to absorb propylene, then intimately contacting under alkylating conditions the acid mixture with said heavy fraction while maintaining an excess of isobutane and acid of alkylation strength in the reaction mixture whereby the isobutane is condensed with the absorbed propylene and C₄ olefins to form high antiknock gasoline hydrocarbons and separating said gasoline hydrocarbons from the reaction products.

10. A process for the manufacture of high antiknock gasoline hydrocarbons, which comprises stabilizing a cracked distillate to produce a light gaseous fraction containing mainly hydrocarbons of less than 4 carbon atoms together with some hydrocarbons of 4 carbon atoms, further stabilizing the distillate to separate a heavy gaseous fraction consisting essentially of hydrocarbons of 4 carbon atoms, scrubbing said light fraction with an oil absorbent to separate hydrocarbons of 4 carbon atoms, further scrubbing the light fraction with concentrated sulfuric acid to separate propylene, contacting under alkylating conditions the acid and propylene mixture with the hydrocarbons of 4 carbon atoms while maintaining the acid at alkylation strength and an excess of isobutane in the mixture, whereby the isobutane is alkylated by the absorbed propylene and C₄ olefins to form high antiknock gasoline hydrocarbons, and separating said gasoline hydrocarbons from the reaction products.

11. A process for the manufacture of high antiknock gasoline hydrocarbons, which comprises separating from a cracked distillate a light gaseous hydrocarbon fraction consisting essentially of hydrocarbons of 3 carbon atoms and lighter including propylene and not more than a small amount of C₄ hydrocarbons, stabilizing the resulting cracked distillate to separate therefrom as a stabilizer distillate at least a portion of the C₄ hydrocarbons including butenes and butanes, treating the light hydrocarbon fraction with concentrated sulfuric acid to absorb the propylene, charging the resulting mixture of sulfuric acid and absorbed propylene to a liquid phase alkylation operation, also charging to the alkylation

unit said stabilizer distillate and sufficient isobutane to bring the ratio of isobutane to olefins in the combined charge to the alkylation operation to at least 1:1, intimately contacting the hydrocarbons with concentrated sulfuric acid of alkylation strength in the alkylation operation whereby the isobutane is alkylated by the olefin compounds and separating from the reaction products saturated high antiknock hydrocarbons of gasoline boiling range.

12. A process for the manufacture of high antiknock gasoline hydrocarbons, which comprises contacting in the liquid phase under alkylating conditions, normally gaseous hydrocarbons consisting mainly of C₄ hydrocarbons including butenes and isobutane with concentrated sulfuric acid of alkylation strength in a reaction zone, introducing into said reaction zone a mixture of propylene absorbed in concentrated sulfuric acid, maintaining in the reaction zone the isobutane in excess of the olefins and the acid at alkylation strength whereby the isobutane is alkylated by the absorbed propylene and butenes to form high antiknock gasoline hydrocarbons and separating said gasoline hydrocarbons from the reaction products.

13. A process for the manufacture of high antiknock gasoline hydrocarbons, which comprises introducing a mixture comprising propylene absorbed in strong sulfuric acid into an alkylation reaction zone containing a butene compound and isobutane maintained under effective C₄ liquid phase alkylating conditions, and maintaining the sulfuric acid in said zone of alkylation strength and the isobutane in molar excess of the equivalent olefin content therein, whereby the isobutane is alkylated by the absorbed propylene and butene compound to form high antiknock gasoline hydrocarbons.

14. A process for the manufacture of high anti-knock gasoline hydrocarbons, which comprises introducing a propylene-sulfuric acid absorption product into an alkylation reaction zone containing a butene compound and a low-boiling isoparaffin maintained under effective C₄ liquid phase alkylating conditions, and maintaining in said zone sulfuric acid of alkylation strength and the low-boiling isoparaffin in molar excess of the equivalent olefin content therein, whereby the low-boiling isoparaffin is alkylated by the propylene-sulfuric acid absorption product and butene compound to form high anti-knock gasoline hydrocarbons.
